**METHOD AND APPARATUS FOR HANDLING
HOSIERY AND THE LIKE**Charles Horberg, Jr., Chicago, Ill., assignor to Paramount
Textile Machinery Co., Kankakee, Ill., a corporation
of IllinoisFiled Nov. 26, 1963, Ser. No. 326,127
18 Claims. (Cl. 223—112)

The present invention pertains to methods and machines for handling hosiery and the like, and more particularly to improvements in a method and in automatic or semiautomatic machines for treating or handling hosiery or other articles on forms, and for thereafter automatically removing the articles from the forms and collecting the articles in a neat and orderly manner.

In the course of hosiery manufacturing and finishing operations, hosiery articles are commonly placed on forms or "boards" and are subjected to one or more processing operations while on the forms. In one such operation, often called "boarding," wet or damp hosiery articles are placed on boards having the shape desired for the finished articles, and are dried thereon while in a stretched or semi-stretched condition. In this manner the hosiery is, in effect, blocked so as to give the hosiery its final desired shape while, at the same time, removing undesired wrinkles and folds from the goods. In other processing operations, hosiery is often "set" on forms or boards by subjecting the goods to steam or other controlled atmospheres, the operation causing the articles plastically to assume the shape of the forms or boards upon which they are mounted.

In all such operations, it has been common in the past manually to pull the stockings onto the forms or boards and also manually to remove the goods from the forms when the processing has been completed. Although mounting the hosiery upon forms by hand has certain advantages in insuring that the hosiery is properly positioned on the forms, the manual removal of the goods from the forms upon completion of the operation has been both laborious and uncomfortable for the operator, particularly because the hosiery and the forms are often still hot when the removal is to be effected. In order to overcome this problem and to speed production, machines have previously been suggested and built for treating hosiery on forms and for thereafter stripping the hosiery from the forms and for collecting the stripped goods. My copending patent application, Ser. No. 258,795, filed Feb. 15, 1963, discloses and claims a highly-improved machine of this type, and the present invention is directed to further improvements in machines of the general character there disclosed and to improvements in the methods of stripping and collecting the hosiery or like articles.

One of the principal objects of the present invention is to provide, in a machine for stripping hosiery and the like from forms, a highly-improved and greatly-simplified means for collecting the stripped hosiery in a neat and orderly manner. In all of the prior machines of which I am aware that have stripped and collected hosiery, the collecting mechanisms have been both relatively complex in structure and relatively expensive to build and maintain. Certain of the prior mechanisms have also had other disadvantages. For example, one of the prior collecting mechanisms, shown in U.S. Patent No. 3,054,542, has employed long needles upon which the hosiery is received and collected, each hosiery article being pierced by the needles as it is collected. This penetration of needles through finished articles has been found objectionable in certain cases where threads have been pulled or

2

broken and where the needle holes remain apparent in the goods after they are removed from the needles.

Accordingly, another object of the present invention is to provide a new and improved method for stripping and collecting hosiery and the like, and, in a machine for stripping hosiery and the like from forms, an improved collecting means which avoids all distortion and damage to the goods.

Still another object of the invention is to provide, in 10 a machine for stripping hosiery and the like from forms, improved collecting means which has a minimum of moving parts, is inexpensive to build, and requires a minimum of maintenance, but yet is durable and reliable.

Yet another object of the present invention is to provide 15 a collecting mechanism having all of the above-designated qualities, and which is ideally located with respect to the operator and is so constructed as to permit quick and easy unloading when a desired number of stockings have been collected thereon.

Still another object of the present invention is to provide 20 in a machine of the above-described character, an improved mechanism for stripping hosiery and the like from forms and for carrying the hosiery to the collecting mechanism.

25 These and other objects and advantages of the present invention will be apparent from the following description of a preferred embodiment thereof, taken with the accompanying drawings wherein:

FIGURE 1 is a perspective view of a hosiery boarding machine constructed in accordance with and embodying and utilizing the present invention, the machine being seen from the front and right side thereof and with a stocking being stripped from a hosiery board or form carried by the machine, after which the stocking will be carried upwardly to be collected upon an illustrated stack of stockings which have been previously collected;

FIG. 2 is an enlarged fragmentary perspective view, taken from the front and slightly to left of the machine, showing the collecting mechanism receiving a stocking which has been stripped from a hosiery board and carried upwardly to collecting position by the hosiery-stripping mechanism;

FIG. 3 is a fragmentary perspective view of the lower front and right side of the machine, showing the stripping mechanism again in position to strip another stocking from a hosiery board, and with certain panels or doors removed from the machine so as to show additional hosiery-bearing boards within the treating chamber of the machine and about to emerge therefrom to the stripping station, and also to show in the lower base portion of the machine certain of the mechanisms employed for driving the stripping and collecting mechanisms;

FIG. 4 is a perspective view of the left side and rear 55 of the machine, with certain panels or doors removed to show a plurality of the hosiery-bearing boards within the treating chamber and another hosiery-bearing form which has just entered the chamber, additional boards being seen at the front portion of the machine;

FIG. 5 is an enlarged fragmentary plan view of the hosiery board transport mechanism in the area adjacent the entrance to the treating chamber, as seen when looking downwardly from approximately the position of the line 5—5 in FIG. 4, certain parts being omitted for simplicity and clarity of illustration;

FIG. 6 is an enlarged fragmentary, vertical sectional view, taken substantially along the line 6—6 of FIG. 1, illustrating the drive mechanism of the machine in the lower portion thereof;

FIG. 7 is a fragmentary vertical sectional view, taken substantially along the line 7—7 in FIG. 6, showing that

portion of the drive mechanism employed for producing the reciprocating motion of the stripping mechanism, and showing a support base for the stripping and collecting mechanism, certain background and other parts being omitted from the view for simplicity and clarity of illustration;

FIG. 8 is a fragmentary vertical sectional view, taken substantially along the line 8—8 in FIG. 6, showing the lower portion of the drive mechanism employed for reciprocation of the hosiery-collecting table or shuttle;

FIG. 9 is a fragmentary vertical sectional view showing certain intermediate drive linkages which are mounted on the support base, and driven by the mechanism illustrated in FIG. 8, for driving the collecting table or shuttle;

FIG. 10 is a fragmentary elevational view of the support base as seen from the front or right of FIG. 9, with the drive mechanism of FIG. 7 being omitted therefrom for simplicity of illustration;

FIG. 11 is an enlarged detailed elevational view of 20 the drive gear for the hosiery board transport system, with an adjustable cam on the upper side thereof for operating an air valve which controls the actuation of a clamp plate in the stripper mechanism;

FIG. 12 is an enlarged detailed plan view of the cam 25 just referred to, together with a schematic representation of the air valve operated thereby;

FIG. 13 is a fragmentary top plan view of the stripper support rails and the collecting mechanism, as seen substantially from the position of the line 13—13 in FIG. 1, the stripper mechanism itself being omitted from the view for simplicity and clarity of illustration, and a portion of the collecting table or shuttle being cut away;

FIG. 14 is a side elevational view of the mechanism illustrated in FIG. 13;

FIG. 15 is an elevational view of the outer or left end of the apparatus of FIGS. 13 and 14, with the collecting mechanism being omitted from the view;

FIG. 16 is an elevational view, partly in section, taken substantially along the line 16—16 in FIG. 1, showing the stripping mechanism and the manner in which it is supported upon the rail system illustrated in FIGS. 13 and 14;

FIG. 17 is a side view of the stripper mechanism as seen from the left of FIG. 16;

FIG. 18 is an elevational side view of the stripper mechanism as seen from the right of FIG. 16;

FIG. 19 is a fragmentary sectional view taken substantially along the line 19—19 in FIG. 17, showing certain details of the stripper construction;

FIG. 20 is a fragmentary sectional view taken substantially along the line 20—20 in FIG. 17;

FIG. 21 is a fragmentary vertical sectional view taken substantially along the line 21—21 in FIG. 18; and

FIG. 22 is a vertical cross-sectional view, in part schematic, taken through the upper portion of the machine to illustrate the treating chamber and the air circulation and heating means which may be employed in connection therewith, a representative hosiery form being shown by broken lines within the treating chamber.

In the drawings there is shown a machine embodying and utilizing the present invention, the machine including a circular base cabinet 10 and an upstanding drying compartment thereon designated generally by the numeral 11, within which hosiery 16 and the like, which has been placed upon boards 12 at the front of the machine, may be dried. The machine is arranged with a conveying mechanism, later to be described, for moving the hosiery boards or forms 12 from the right to the left across the front of the machine. An operator stands at the front of the machine and slips hosiery to be treated downwardly over the boards 12 as the boards move across the front of the machine, a supply of hosiery to be treated being provided in a readily-accessible location within a trough 13 provided on the front of the machine. The hosiery

5 deposited upon the boards 12 is carried with the boards, one after another, into the drying or treating chamber 11 at the left side of the machine for processing. The hosiery boards, with the stockings thereon emerge, one after another, from the treating chamber 11 at the right of the front of the machine, and, as each board emerges from the treating chamber 11, it reaches a stripping position or zone and the stocking thereon is automatically stripped from the board by a reciprocating stripping mechanism designated generally by the numeral 14. This stripping mechanism 14 will be described in detail later herein, but, at the outset, it may be pointed out that the stripping mechanism is carried or moved upwardly and forwardly during a stripping stroke to strip the stocking from each form, each stocking being collected from the stripping mechanism 14, by a reciprocating transversely moving collecting mechanism 15, when the stripping mechanism reaches the top of its stroke. The transport mechanism, which carries the hosiery boards 12 with the hosiery 10 15 20 25 30 35 40 45 50 55 60 65 70 75 80 85 90 95 100 105 110 115 120 125 130 135 140 145 150 155 160 165 170 175 180 hand wheel 41 secured to its outer end. The inner end of the shaft 49 is coupled, by a coupling 42, to one end of a thread shaft 43 which extends through and is threadedly received by an internally-threaded collar 44 provided on the lower portion of the previously-mentioned bracket 29. The other end of the threaded shaft 43 is rotatably fixed in the motor-hanger bracket 32, it thus being understood that, by manually rotating the wheel 41, the motor-hanger brackets 32 and 33 and the motor 34 thereon may be moved selectively to the right or to the left, as viewed in FIG. 6, thereby to vary the speed at which the variable-speed V-belt pulley 35 drives the V-belt 36 and the speed-reducing unit 38.

A transport drive shaft 45 extends vertically from the speed-reducing unit 38 through an appropriate opening in the heavy base plate 26 and is journaled in a bracket portion 46 of a conveyor track 47, the upper end of the shaft 45 having fixed thereon a drive gear 48, upon the top of which there is secured a stripper timer cam 49. The cam 49, as will be explained hereinafter, controls the gripping action of the stripper mechanism 14 upon the hosiery 16 when the hosiery is gripped and stripped from the hosiery boards 12, the gripping action being subsequently released in timed relation to the collecting movement of the collector mechanism 15, thereby to release the stripped stocking at the proper time to be received upon the collecting mechanism 15.

The transport mechanism for carrying the hosiery boards 12 may be of any suitable construction providing proper movement or advancement of the hosiery boards, and, in the present instance, the transport mechanism shown is that which is illustrated, claimed, and described in detail in my co-pending patent application, Ser. No. 258,795, filed Feb. 15, 1963. This transport mechanism is comprised, broadly speaking, of an endless chain of pivotally-interconnected links 53 and 54, the alternate links 53 having suitably secured thereto the upstanding hosiery boards 12. As will be explained in greater detail hereinafter, the links 53 and 54 ride on rollers carried in the endless conveyor track 47, the links being pushed into the treating chamber 11 by the action of the drive gear 48. As the links are pushed into the treating chamber 11, the links are permitted to pivot with respect to each other and to collapse, so that the hosiery boards or forms 12 within the treating chamber 11 are, in effect, stacked side by side in a close, relatively-compact arrangement, in which condition the hosiery carried by the boards may be subjected to a drying action or any other suitable treatment desired. At the same time the links are being pushed into the treating chamber 11 at the left front side of the machine, corresponding links and hosiery boards are being pulled from the treating chamber 11 at the right side of the machine, thereby withdrawing the hosiery boards 12 successively from the treating chamber and into hosiery-stripping position, and thereafter into position at the front of the machine where the operator will apply another stocking to each freshly-stripped form or board.

The conveyor track 47 is endless and is preferably circular in shape except for a straight section thereof which extends from within the treating chamber at the right side of the machine, forwardly through the exit from the treating chamber and to the zone where the stripping from the hosiery boards takes place. The track 47 (FIG. 6) is provided with an upper channel 50 and a lower channel 51, the channel 51 being more narrow than the channel 50, thereby providing a shoulder 52 where the two channels join. As suggested above, the transport mechanism includes board-carrying links 53, each board-carrying link 53, at its opposite ends, resting upon and being pivotally connected to the ends of successive intermediate links 54. It is thus to be understood that the level of the links 54 is lower than that of the board-carrying links 53. Pivot pins 55 (FIG. 5) which pivotally join the successive links, have on their respective lower ends a roller 56 which rides in the upper channel 50 and is supported by the shoulders

52. Each pin 55 which is disposed at the trailing end of each board-carrying link 53, additionally carries another roller (not shown) of smaller size than the roller 56. This additional roller is beneath a roller 56 and rides in the lower channel 51 of the transport or conveyor track 47. Each of the links 53 and 54 has a longitudinal curvature corresponding to the curvature of the circular portion of the track 47, and the outer-edge portion of the track 47 is covered by a curved plate 57 which overlies or overhangs the upper channel 50. The overhanging of the plate 57 with respect to the upper channel 50 of the transport track causes the plates 57 to overlie the rollers 56 and thus prevent the rollers 56 and the links and the hosiery boards 12 from being dislodged from the track 47. The inner edge of each link 53 and 54 is provided with teeth 60 which correspond and are adapted to mesh with the teeth on the transport drive gear 48. The links 53 and 54 are thus driven by the drive gear 48, as shown in FIG. 5, the drive gear 48 being adapted to be rotated by 15 the speed-reducing unit 38 in a clockwise direction. Opposite the position of the drive gear 48, a plurality of back-up rollers 61 may be mounted to bear against the outer surface of the successive links 53 and 54 as the teeth 60 on the links come into mesh with the teeth of the drive gear 48.

As seen in FIG. 5, the links are driven in the direction of the arrow 62, the links moving into the treating chamber 11 through an opening 63 provided in an upstanding vertical wall 64 which forms the front wall of the treating 20 chamber. The opposite vertical edge portions of the opening 63 are preferably provided with flexible neoprene or rubber sheets 65 which serve to close the opening 63 to prevent hot air or the like from emerging from that opening, but yet permit the links 53 and 54 and the hosiery boards 12 to be pushed by the drive gear 48 into the treating 25 chamber 11.

Just inside the treating chamber 11 adjacent the opening 63, the outer wall of the upper channel 50 of the conveyor track 47 is cut out to provide therein an exit opening 66 for the roller 56 at the leading end of each board-carrying link 53. It will be understood that beneath each roller 56 at the leading end of each link 53 there is no lower roller riding in the lower channel 51 of the track 47. Thus, as the links 53 and 54 are pushed into the treating 30 chamber 11, the pushing force causes each link 53 to tend to buckle outwardly with its next preceding intermediate link 54. As the roller 56 at the leading end of each link 53 comes to a position in registry with or opposite the opening 66 in the outer wall of the upper channel 50 of the conveyor track, that roller 56 moves outwardly of the track 47 and thus permits the links 53 and 54 to buckle with respect to each other. The path followed by the roller 56 at the leading end of each board-carrying link 53 during the buckling is represented by the 35 path of the arrows in FIG. 5. As the pairs of links 53 and 54 buckle with respect to each other, the under side of each preceding intermediate link 54 slides across the flat surface of a curved support plate 67, thereby permitting the links 53 and 54 to be moved successively into the side-by-side stacked position illustrated in the upper portion of FIG. 5. The trailing end of each link 53, it will be noted, continues to follow the track 47 because of the lower roller therebeneath which remains in the lower channel 51 of the track. As each successive pair of links 53 and 54 is caused to buckle and to be pushed into stacked position, the entire group of stacked links and the upright hosiery forms thereon are advanced within the treating chamber 11 a distance approximately equal to the width of one link. Accordingly, it will be appreciated that the movement of the links and forms 12 through the treating chamber is quite slow and intermittent, although the movement of the links and forms outside the chamber is continuous and at a more rapid rate.

As previously suggested, as the links 53 and 54 and the hosiery boards 12 are being moved into and stacked and

advanced within the treating chamber 11, corresponding links 53 and 54 and hosiery boards 12 are being withdrawn from the opposite side of the treating chamber 11. The area where this withdrawal operation takes place is best seen in the central foreground of FIG. 3. The conveyor track 47 exteriorly of the treating chamber 11 is covered on its front and back sides by a protective shell 70, the upper portion of the shell 70 being open and provided with flexible converging strips of neoprene or rubber-like material 71, the latter of which permits free movement of the hosiery forms 12, but yet prevents foreign objects from being dropped downwardly onto the track 47 and the links 53 and 54. As perhaps best seen in FIG. 3, that portion 70a of the shell 70 covering the track 47 at the exit from the treating chamber 11 is straight, and the track 47 within the shell portion 70a is likewise straight, the straight portion of the track extending a short distance into the treating chamber 11.

In the stacked condition of the links within the treating chamber 11, the rollers 56 at the outer ends of the board-carrying links 53 ride on the outer lip portion 71 of a secondary or outer track 72 (FIG. 5). This secondary or outer track 72 follows the curvature of the track 47 within the treating chamber, but terminates just short of the straight portion of the track 47 just mentioned. As the rollers 56 at the outer ends of the links 53 move off of the terminal portion of the outer or secondary track 72, the pulling force exerted by the drive gear 48 on the chain of links in the area of the exit from the treating chamber 11 causes the successive buckled links 53 and 54 to unbuckle and, in effect, straighten out. This straightening out of the buckled links 53 and 54 is assisted by a switch bar 73 which, as seen in FIG. 3, is disposed at an angle with respect to the straight portion of the track 47 adjacent the exit from the treating chamber 11. The rollers 56 which have been riding upon and following the secondary track 72 bump the diagonally-disposed switch bar 73 and are thus guided or restored to the upper channel 50 in the straight portion of the track 47 through an opening (not shown) in the outer wall of the upper channel 50 of the track corresponding, in essence, to the opening 66 through which these rollers left the confines of the upper channel 50.

After the links 53 and 54 are straightened out and the rollers 56 thereon are restored to the upper channel 50 of the track 57, the links and the upstanding hosiery boards 12 are withdrawn from the treating chamber 12 through an exit opening 74 in the front wall 64 of the treating chamber 11. This front opening 74 is preferably provided with a pair of converging neoprene or rubber-like flexible sheets 75 which protrude outwardly with respect to the opening 47 and serve to close the opening, while permitting the hosiery forms 12 and the hosiery items 16 thereon to emerge freely from the treating chamber 11 to the stripping zone.

The treating chamber 11 may be of any suitable structure. In the present instance, the sides and rear portion of the treating chamber are provided with a plurality of removable doors 80, which are shown, for the most part, to be removed in FIGS. 3 and 4, in order that the interior of the treating chamber and the stacked hosiery forms and links may be seen. The upper portions of the sides of the treating chamber are closed by a plurality of permanent panels 81, and the top of the treating chamber is closed by a top wall 82. This top wall 82 is shown in FIG. 22, where there is illustrated a largely schematic arrangement by which hosiery may be dried and/or heat-treated within the present embodiment of the machine. As there seen, an electric motor 83 may be mounted upon and below the base plate 26 and arranged to drive a fan 84 mounted upon a shaft 85. The shaft 85 may be carried in a suitable bearing provided on a bracket 86, the latter of which may be suitably mounted upon the upper surface of the base plate 26 within the treating chamber 11. The fan in the present instance is arranged to blow

air upwardly through a cylindrical passage 87 and into an upper interior chamber 88, from which a portion of the air may be expelled through an opening 89 in the upper wall 82 of the treating chamber. The major portion of the air, however, may be caused to pass downwardly through a set of heat-exchange coils 90. The heated air emerging from the lower side of the group of heat-exchange coils 90 may then pass downwardly over the stacked, upstanding hosiery forms 12, in order to dry or otherwise treat hosiery carried by the forms, and then back to the fan 84, as shown in FIG. 22. That portion of the heated and moist air expelled from the treating chamber 11 through the opening 89 in the top 82 of the chamber may be replaced by air drawn into the treating chamber 11 from the interior of the lower of base portion 10 of the machine through a suitable opening provided in the base plate 26 about the shaft 85.

The inner sides of the removable panels 80, which close the sides and rear of the treating chamber 11, may be provided with inwardly-directed baffles 91, so as to provide a venturi effect in the area adjacent the hosiery forms 12.

The top wall 82, and the front wall 64, as well as the fixed panels 81 and the removable panels 80, may be insulated in any way desired. In FIG. 22, insulation is shown in the interior of the upper wall 82, although for convenience of illustration it has been omitted from the representations of the front wall 64, the panels 81 and the removable panels 80.

Turning now to FIG. 6, it will be observed that a drive shaft 100 extends from the lower end of the speed-reducing unit 38 and is coupled, by a flexible coupling 101 or the like, to a vertically-disposed shaft 102 of a miter gear assembly 103. The miter gear assembly 103 is suitably mounted in any convenient manner upon the I-beams 27 and 28 and has a drive shaft 104 extending horizontally therefrom to the right, as viewed in FIG. 6. The drive shaft 104 is coupled, by a coupling 105, to one end of another drive shaft 106, the opposite end of which is supported in a bearing assembly 107 contained in the upper portion of an upstanding standard 108 which is mounted between the I-beams 27 and 28 upon a heavy plate 109 secured to the under sides of the I-beams 27 and 28. The extremity of the shaft 106, beyond the standard 108 and its supporting bearing 107, has fixed thereon a crank 110 which has on its outer end a cam-follower roller 111. This crank 110 and the cam-follower roller 111 serve to drive, in reciprocation, a stripper drive arm 112. As best seen in FIGS. 6 and 7, the stripper drive arm 112 is pivotally mounted at its lower end upon a horizontally-disposed pin 113 carried in the upstanding legs of a U-shaped block 114 mounted between the I-beams 27 and 28 on the heavy plate 109 previously mentioned. The stripper drive arm 112 extends generally rearwardly and upwardly from the area occupied by the I-beams 27 and 28, as illustrated in FIG. 7, and the I-beam 28 may be cut out, as at 28a (FIG. 7), to avoid any interference between the I-beam 28 and the stripper drive arm 112 during reciprocating movement of the latter.

In FIG. 7 the stripper drive arm 112 is shown in solid lines in a rearward or retracted position and is illustrated by broken lines in an advanced position, these illustrations of the stripper drive arm 112 representing nearly the extent of the stroke through which the drive arm is moved during one cycle of its operation, i.e., during one complete revolution of the shaft 106. As will be explained more fully hereinafter, the solid-line position of the stripper drive arm 112 seen in FIG. 7 corresponds to the position of the stripper mechanism 14 momentarily after it has left its lowest position and has just begun to advance upwardly, at which time the stripper mechanism 14 grips a stocking 16 on one of the hosiery boards 12 and thereupon begins to strip the stocking from the hosiery board as the stripper arm 112 continues to move from its solid-line position in FIG. 7 toward its broken-line position. The broken-line position of the stripper arm 112 in FIG. 7, on the other hand, corresponds to the

position of the stripper mechanism 14 shortly before it reaches its uppermost position illustrated in FIG. 2, wherein the stocking 16 has been fully stripped from a hosiery board 12 and has been carried upwardly by the stripping mechanism 14 to the collecting position, wherein the stripping mechanism 14 is caused to release its grip from the stocking and permit that stocking to be received upon the collected mechanism 15.

In order to accomplish the reciprocation of the stripper drive arm 112 referred to above, the stripper drive arm has formed on the upper side thereof, adjacent its lower end, an upstanding side flange 112a upon which there is secured a cam member 115 having formed therein a "banana-shaped" cam race 116 in which the cam-follower roller 111 on the crank arm 110 rides. Those skilled in the art will immediately recognize that, as the crank arm 110 is caused to rotate by the rotation of the shaft 106, the cam-follower roller 111 will drive the cam member 15, and thus the stripper arm 112 in the reciprocating path described above. The "banana-shaped" cam race 116 is provided with the particular shape illustrated in FIG. 7, in order, not only to produce the reciprocation just referred to, but also to produce a dwell period in the movement of the stripper drive arm 112 at both ends of its stroke. Momentarily before the solid-line position of the crank arm 110 in FIG. 7 is reached, the cam-follower roller 111 will have passed the position within the cam race 116 at which the stripper arm 112 reverses its direction of movement and starts to advance in a forward direction, that is, from left to right as seen in FIG. 7. The stripper drive arm 112 dwells momentarily as it reverses its direction when it reaches the full-line position of FIG. 7, the stripper drive arm 112 will be moving slowly, but will be accelerating in the direction toward its broken-line position as the cam-follower roller 111 progressively moves downwardly into the lower portion of the cam race 116. When the roller 111 reaches the bottom of the cam race 116, the stripper drive arm 112 will have its greatest forward speed, and, as the roller 111 begins thereafter to raise from the bottom of the race 116, the drive arm 112, which will still be advancing toward its forwardmost position, will begin to decelerate.

The drive arm 112 will reach its most forward position and will dwell momentarily when the roller 111, in its movement up the cam race 116, reaches the center of the cam race. The arm 112 will thus dwell in its forwardmost position, while the stripped stocking 16 is being received upon the collecting mechanism 15. Thereafter, as the roller 111 passes through the central portion of the cam race 116 and into the upper portion of the cam race, the return movement of the arm 112 will begin, this movement being accelerated until the cam roller reaches the uppermost end of the cam race 116, at which point the arm 112 will be at the halfway point in its return movement. As the roller 111 thereafter begins to return from the uppermost end of the cam race 116 toward the center thereof, the arm 112 will continue to move rearwardly toward its most rearward position, but this remaining portion of the return stroke will be at a decelerating pace.

The cam race 116 is so shaped, and the speed of rotation of the shaft 106 is so proportioned with respect to the drive speed of the hosiery form transport mechanism that the horizontal forward component of movement of the stripping mechanism 14, at the beginning of a stripping stroke of the drive arm 112 and the stripping mechanism 14 driven thereby, is approximately equal to the horizontal speed of the hosiery board 12 being stripped in the hosiery-stripping zone immediately outside the exit opening 74 of the hosiery-treating chamber 11. Thus, in the initial movement of the stripping mechanism 14, the gripping jaws therein, which will later be described in detail, grip the foot portion of a stocking 16 on a form 12 and effectively lift that foot portion of the stocking substantially vertically with respect to the form, thereby partially to clear the heel portion of the stocking 16 from

the heel portion of the form 12. As the stripping operation proceeds, the stripping stroke of the stripping mechanism 14 accelerates, thereby to strip the stocking forwardly and upwardly off of the hosiery form 12.

5 The connection between the stripper drive arm 112 and the stripping mechanism 14, is comprised of a stripper pusher rod 120. The lower end of the pusher rod 120 is pivotally connected to the extremity of the drive arm 112, and the upper end of the pusher rod 120 is pivotally connected, by a pin 121, to a yoke 122 formed on the under side of a bearing assembly 123 provided on the stripper assembly 14 and adapted to slide on a stripper slide rod 124, the mounting of the latter of which will presently be described. The stripper push rod 120 extends upwardly through an opening 26a (FIG. 6) in the heavy base plate 26, this opening also accommodating the upper portion of the stripper drive arm 112 when the latter is in the upper reaches of its stroke. The push rod 120 also extends through an opening (not shown), in the front wall 64 of the treating chamber 11.

10 Due to the fact that the stripper drive arm 112 is, in all of its positions, disposed rearwardly of its pivotal mounting on the pin 113, the stripper arm 112 may be provided with a counterbalancing coiled tension spring 125, one end of the tension spring being connected to the upper edge of the flange 112a of the stripper arm 112, and the opposite end (not shown) being fixed in any suitable manner as, for example, to the under side of the heavy base plate 26. The use of the spring 125 is entirely optional, but it may be used to counterweight the stripper drive arm 112 if desired.

15 As illustrated in FIGS. 6 and 8, the shaft 106 also has fixed thereon a cam wheel 126 having formed on one face thereof an eccentric cam race 127 for operating a cam-follower roller 128 this cam-follower roller being mounted upon one side of a collector mechanism drive arm 129 which has one of its ends pivotally mounted upon a pin 130 (FIG. 8) which extends horizontally between a pair of brackets 131 (FIG. 6) fixed in any suitable manner upon the upper surface of the I-beam 27.

20 Thus, it will be understood that, as the shaft 106 is rotated, the arm 129, which extends generally rearwardly with respect to the I-beams 27 and 28, will be raised and lowered, due to the shape of the cam race 127 in the cam wheel 126. This raising and lowering of the arm 129 is utilized to drive the collector mechanism 15 in a reciprocating motion which will be described in more detail later.

25 To this end, however, it may now be observed (FIGS. 8 and 9) that a first collector push rod 132 has its lower end pivotally secured to the free end of the arm 129, the uppermost end of the push rod 132 being pivotally connected to a bell crank 134. This bell crank 134 is pivotally mounted upon a pin 135 (FIG. 10) which extends horizontally from one side of a rigid

30 upstanding support frame member 136, preferably in the form of a casting securely mounted upon the heavy base plate 26 within the treating chamber 11 immediately to the rear of the front wall 64 thereof. The push rod 132, it will be seen, extends upwardly, from the drive arm 129 to the bell crank 134, through an appropriate opening 26b provided in the heavy base plate 26.

35 As the collector drive arm 129 is reciprocated in an up-and-down motion during the rotation of the shaft 106 and the cam wheel 126, the push rod 132 causes the bell crank 134 to reciprocate in a pivotal motion about the pin 135. This pivotal motion of the bell crank 134 is utilized to produce the reciprocating motion of the collector mechanism 15, by means of a linkage mechanism later to be described which includes a second collector

40 push rod 137 that has its lowermost end pivotally connected to the free end 134a of the bell crank 134, the second push rod 137 extending diagonally upwardly and forwardly through an opening 64a (FIG. 1) in the front wall 64 of the treating chamber 11.

45 Referring particularly to FIGS. 7 and 10, the rigid stripper support rod 124 extends diagonally upwardly

and forwardly through the front wall 64 of the treating chamber, the lowermost end of the rod 124 being very securely mounted upon the upstanding frame member 136 by means of heavy clamps 140 provided on one side of the frame member 136. These clamps 140 are of ordinary construction and need not be described in detail, in view of their illustration in FIGS. 7 and 10.

The stripper support rod 124, forwardly of the front wall 64 of the treating chamber, has a clamp 141 thereon (FIGS. 2 and 13). This clamp 141 has an arm 142 formed thereon, which extends laterally with respect to the rod 124, the outermost end of the arm 142 having secured thereto, as by screws 143 (FIG. 13), a stripper guide and stabilizing bar 144. This bar 144 is generally rectangular in cross section and extends from the arm 142 parallel to the support rod 124. The uppermost ends of the rod 124 and the bar 144 are secured to and carry a rigid casting member 145 of inverted L-shape, the casting being secured to the outermost end of the rod 124 by a pair of screws 146 and to the outermost end of the bar 144 by one or more screws 147. The support rod 124 and the stabilizing and guide bar 144 are thus rigidly mounted and secured together and, as will presently be explained, they serve as a track upon which the stripping mechanism 14 rides.

The stripping mechanism 14 includes the previously-mentioned bearing member 123, which slides upon the support rod 124 and is driven by the previously-described push rod 120. The upper side of the bearing member 123 is flat and has secured thereto, as by screws 150 (FIG. 16), a plate 151 which serves as a frame for the various elements of the stripper mechanism 14. The plate 115 has fixed on its under side a depending block 152 which has mounted on one side thereof a pair of rollers 153 that ride on the upper and lower surfaces of the stabilizing and guide bar 144. Thus, it will be seen that, as the stripper push rod 120 is reciprocated by the mechanism previously described, the bearing member 123 will slide back and forth along the heavy support rod 124 and the rollers 153 will ride back and forth along the guide and stabilizing bar 144 while, at the same time, giving the plate 151 full support and stability.

At the right side of the plate 151, as viewed in FIGS. 2 and 16, a block 155 is securely mounted beneath the plate by means of spacer members 156 and screws 157. The outer lateral surface of the block 155 has secured thereto, as by screws 158, a depending plate 159 which serves as a stationary outer gripping jaw for the stripping mechanism 14. The shape of this stationary jaw 159 is best illustrated in FIG. 18, it being observed that the rearmost end of the plate is flared out at 159a and that the lower portion of the plate provides a depending skirt having a substantially-horizontal lower edge (FIGS. 1 and 2).

On the side of the block 155 opposite the plate or jaw 159, there is secured a heavy depending plate 160, the lower end of which is rounded, as at 160a. On the inner surface of the plate 160 an inflatable diaphragm 170, of rubber or the like, is mounted by means of a circular ring 171, the circular ring being secured to the inner surface of the plate 160, as by screws 172 (FIG. 20), the circular ring 171 overlying the periphery of the diaphragm 170 and clamping the periphery of the diaphragm to the plate 160 in an air-tight manner. A flexible air line 173, of plastic, neoprene, or the like, extends from an air connection 174, provided on the forward face of the front wall 64 of the treating chamber 11 (FIG. 1), through an opening 151a in the plate 151 of the stripper mechanism 14 (FIG. 16) and to a standard air-line fitting 175 (FIGS. 17 and 19) threaded into an opening 176 provided through the plate 160 beneath the diaphragm 170. Thus, it will be appreciated that compressed air may be applied through the air line 173 to the under side of the diaphragm 170 to cause the diaphragm to bulge or be inflated outwardly from the plate 160 toward the fixed

plate or jaw 159 of the stripping mechanism. This inflation of the diaphragm 170 is utilized to actuate a movable gripping jaw 177 of the stripping mechanism.

The movable gripping jaw of the stripping mechanism 14 is comprised of a plate 178 which overlies the diaphragm 170 and is fixed upon the ends of a pair of pins 180 (FIG. 19) that extend through the plate 160 and are slidably mounted therein in bearings 181, the innermost end portions of the pins 180 being free to pass through suitable openings provided in the circular diaphragm 170. The respective outer ends of the pins 180 have washers 182 fixed thereon, and beneath these washers each pin 180 is provided with a compression spring 183. The outer end of each compression spring 183 is adapted to bear upon the corresponding fixed washer 182, and the inner end of the compression spring is seated in a recess provided in the plate 160. Thus, it will be understood that the pins 180 are constantly urged outwardly (as seen in FIG. 19) by the springs 183, thereby causing the plate 178 to be urged toward an open position with respect to the fixed plate or jaw 159 of the stripping apparatus. The force of the springs, however, is overcome when the diaphragm 170 is inflated, thereby moving the plate 178 and the entire movable jaw 177 toward the jaw 159 and into clamping relation thereto.

If desired, the respective pins 180 and their co-operating springs 183 may each be covered by a cap 184, the caps being threadedly received in the recesses in the plate 160 within which the springs 183 are seated. The outermost end of each cap 184 threadedly receives a set screw 185, the innermost end of which is adapted to abut the outermost end of the corresponding pin 180. Thus, the set screws 185 may be utilized to adjust the fully-open position of the plate 178.

The inner surface of the movable plate 178 of the movable jaw 177 of the stripping mechanism has adhesively or otherwise secured thereto a layer 190 of soft spongy polyurethane or the like, and on the outer surface 40 of the layer 190 there are secured two strips of mohair or the like, 191 and 192. The strip 191 of mohair is adhesively or otherwise secured to the layer 190 in a position such that the natural nap of the mohair is directed toward the front of the stripping apparatus, as seen 45 in FIG. 19. The strip 192 of mohair is positioned upon the layer 190 in the area thereof which will contact the heel portion of a stocking 16 on a board 12 when stripping is about to take place, and the nap of the mohair strip 192 is arranged, so that the nap is directed upwardly, as shown in FIG. 21. Corresponding sections 50 of mohair 193 and 194 are adhesively or otherwise secured to the inner side of the stationary plate or jaw 159 of the stripping mechanism, the mohair strip 193 being disposed opposite the strip 191 with its nap being directed 55 forwardly. Similarly, the mohair strip 194 is positioned opposite the strip 192, and its nap, like the nap on the strip 192, is directed upwardly.

In view of the foregoing description of the stripper mechanism 14, it will be understood that, when the stripper mechanism is moved downwardly to its stripping position, the fixed jaw 159 and the movable jaw 177 of the stripper mechanism will straddle the upper portion of a hosiery form 12, and the stocking thereon, both of which have just emerged from the treating chamber 11. 60 With the jaws in this straddling position, wherein the mohair strips 191 and 193 are on opposite sides of the foot portion of the stocking, and the mohair strips 192 and 194 are on opposite sides of the heel portion of the stocking, the diaphragm 170 is inflated to actuate the movable jaw 177 and thus clamp the stocking between the two jaws for stripping purposes. The previously-described stripping motion of the stripping mechanism thereupon begins and first tends to raise the foot and heel 65 portions of the stocking directly upwardly with respect 70 to the stationary plate 151.

to the moving hosiery form and thereafter forwardly with respect thereto, to strip the stocking from the form.

This inflation of the diaphragm 170 and the clamping operation of the stripper mechanism are controlled in proper timed sequence and relationship to the movement of a form 12 into stripping position, by means of the previously-mentioned cam 49 (FIGS. 5, 6, 11 and 12) which is fixed upon the upper end of the transport drive shaft 45 above the transport drive gear 43. As perhaps best seen in FIG. 12, the cam 49 has a low peripheral portion 49a thereon and a raised peripheral portion 49b thereon. The cam 49 moves in a clockwise direction, as viewed in FIG. 12, and is adapted to actuating a roller 200 of an air-control switch valve 201 of a commercially-available type. As illustrated in FIG. 12, the roller 200 is shown to be riding on the lower portion 49a of the cam. In this condition of the roller, the switch valve 201 has closed a valve 202 provided in an air line 203 and has exhausted the air pressure from the line 203, it being understood that the line 203 leads to the air connection 174 on the front side of the forward wall of the treating chamber 111 and thus also to the flexible air line 173 which leads to the stripper mechanism 14. Consequently, when the roller 200 is riding on the low portion 49a of the cam 49, the diaphragm 170 of the stripper mechanism is deflated, and the movable jaw 177 of the stripper mechanism is in its open position. When the roller 200 rides up onto the raised portion 49b of the cam 49, the switch valve 201 actuates the valve 202 to introduce air under pressure into the line 203, and thus beneath the diaphragm 170, through the flexible air line 173, thereby causing the diaphragm 170 to be inflated and to cause the jaws of the stripper mechanism 14 to close. The cam 49 is provided with a movable and adjustable quadrant 49c which, as illustrated in FIG. 12, may be adjusted rotatably with respect to the body of the cam 49 to increase or decrease the peripheral length of the raised portion 49b of the cam. Accordingly, the period during which the diaphragm 170 is inflated and the jaws of the stripper mechanism are closed may be varied, by adjusting the position of the quadrant 49c. It will be appreciated that, by rotating the quadrant 49c in a clockwise direction with respect to the cam 49, the time will be shortened during which the jaws of the stripper mechanism are in clamping position upon a stocking. Conversely, by adjusting the cam quadrant 49c in a counterclockwise direction with respect to the cam 49, the duration of the clamping action of the jaws of the stripper mechanism upon a stocking will be increased. This adjustable positioning of the cam quadrant 49c is useful in adjusting the stripping mechanism so that it will release a stocking at the desired precise moment, whereby the stocking may properly be received in a stacked condition upon the collecting mechanism 15.

In conjunction with the mohair strips 191, 193 and 192, 194 and the previously-described directions of their naps, it is to be pointed out that the nap direction in each case is in the direction of the pull exerted upon stocking during the stripping operation. Thus, during the initial portion of the stripping movement, at which time a lifting force is exerted upon the stocking, the upwardly-directed naps of the mohair strips 192 and 194 are projecting in the direction of the lifting force applied to the heel portion of the stocking, and the nap direction tends to prevent the heel portion of a stocking from being pulled out of the jaws of the stripping mechanism. During the later phase of the stripping operation, when the stocking is pulled upwardly and forwardly off of a hosiery form 12, the forward direction of the naps of the mohair strips 191 and 193 assist in holding the stocking and preventing it from slipping rearwardly between the jaws of the stripping mechanism.

Turning, now, particularly to FIGS. 2, 13, 14, and 15, where the collecting mechanism 15 and its operating linkages are best illustrated, it will be noted that the forward-

most end of the collector push rod 137 is provided with a terminal end connection 225 having a ball bearing 226 or the like therein (FIG. 15) which receives a bolt 227. The shank of the bolt 227 extends through the bearing 226 and also through a slot 228 formed in an arm 229 which is fixed upon the lower end of a shaft 230 that is rotatably mounted in, and extends entirely through, the left end of the inverted L-shaped casting 145, as viewed in FIG. 15. The bolt 227 is provided with a nut 231 which may be drawn up tightly to cause the lower surface of the bearing 226 to bear against the upper surface of the arm 229. It will thus be understood that by loosening the nut 231, the position of the bolt 227 may be adjusted within the slot 228, thereby to adjust the amount of swing or the length of stroke which will be effected in the arm 229 upon reciprocation of the push rod 137. This adjustment, it will later be seen, serves to vary and adjust the extent of the swing, reciprocating stroke of the collector mechanism 15.

The upper end of the shaft 230 (FIG. 13) has fixed thereon a crank arm 232, the outer end of which is pivotally connected to one end of a link 233. The opposite end of the link 233 is pivotally connected to the outer end of another crank arm 234 which is fixed to the upper end of a shaft 235 that is rotatably carried in, and extends entirely downwardly through, the right-hand leg 145a of the inverted L-shaped casting or frame 145, as viewed in FIGS. 2 and 15. The back side of this right-hand leg 145a is provided with a recess 145b (FIG. 14), through which the shaft 235 extends, a suitable bearing 236 being provided for the shaft in the upper wall of this recess and a corresponding bearing 237 being provided for the shaft 235 in the lower wall of the recess. The lowermost end of the shaft 235 protrudes from the lower wall of the recess 245b and to a position below the bottom face 145c of the leg 145a of the inverted L-shaped frame member 145. This protruding portion of the shaft 235 has fixed thereon an arm 238 which has a socket 239 therein that receives one end of a rod 240, the rod 240 being removably fixed within the socket 239 by means of set screws 241 or the like. The rod 240 (FIGS. 2 and 14) extends diagonally rearwardly and downwardly from the arm 238 and is formed to provide a generally downwardly directed element 241. At the lower end of this element 241 the rod 240 is formed to provide a generally horizontally and rearwardly directed element 242. This latter element 242 has welded or otherwise fixed thereto a downwardly-directed lip 243 of a preferably saddle-shaped shuttle or collecting table 244, it being understood that the table 244 is fixed to and supported by the lip 243 and, in turn, is fixed to and supported by the rod 240.

The table 244, as previously mentioned, is preferably somewhat saddle-shaped, in that it is provided with a slight longitudinal bow in the direction from the free end of the table to the end at which the lip 243 is located, and the forward lateral edge of the table may be longitudinally curved and provided with a low upstanding side lip 245. The upper surface of the table 244 is preferably provided with a plurality of longitudinally spaced apart, transversely extending mohair strips 246, the naps of which are preferably directed toward the free end of the table, and the free end of the table is preferably provided with a relatively-large notch 247 which extends into the body of the table to a position overlaid by the toe portions of the stack of stockings 16a collected upon the table. By virtue of the notch 247, an operator may quickly and easily grip the toe portions of the stack of stockings 16a between a thumb and forefinger while the stack is on the table, and may thereupon quickly and easily remove the stack without stopping the machine and without disturbing the stacked relationship between the goods.

Referring again to FIG. 14, the recess 145b in the leg 145a of the casting or frame 145 may be covered by a side plate 250, and within the lower portion of the recess 145b a hub 251 of a clamp plate arm 252 is rotatably

mounted upon the shaft 235. The lower surface of this hub 251 bears upon the upper race of a ball bearing assembly 253 that encompasses the shaft 235 and rests against the lower wall of the recess 145b. The clamp arm 252 is thus free to rotate about the shaft 235 independently of any rotation of the shaft itself. A coil spring 254 encompasses the shaft 235 within the recess 145b, the upper end of the spring 254 being anchored in the upper wall of the recess, and the lower end of the spring being anchored in the hub 251 of the clamp arm 252. This coil spring 254 is so tensioned, at its installation, as to constantly urge the clamp arm 252 toward the left, as viewed in FIG. 2. The movement of the clamp arm 252 toward the left, however, is limited by a stop wing 251a (FIG. 2) which is formed on one side of the hub 251 of the clamp arm. This stop wing 251a preferably has provided on its face a resilient button 251b that is adapted to engage the rearwardly-protruding end of an adjustable stop-screw 145c that is threaded through a wing 145d formed on the left-hand lower side of the leg 145a of the casting or frame 145, as illustrated in FIG. 2. The adjusting screw 145c is adjusted to be engaged by the button 251b on the stop wing 251a when the clamp arm 252 has been swung to the left, as viewed in FIG. 2, to a position slightly to the right of a vertical plane passed downwardly between the jaws of the stripping mechanism 14.

The free end of the clamp arm 252 is provided with a clamp plate 260 that is in the path of the lip 243 of the collecting table 244. The inner surface of the clamp plate 260, opposite the face of the lip 243, is preferably provided with a layer of mohair fabric 261.

In view of the foregoing description of the collector mechanism 15, it will be understood that, as the drive shaft 106 (FIG. 6) rotates, and as the cam wheel 126 thereon is turned, the collector drive arm 129 (FIG. 8) is moved up and down to reciprocate the push rod 132 and thus the second push rod 137. The reciprocation of the push rod 137 moves the crank arm 229 back and forth, and the same motion is translated to the arm 232 by the shaft 230. The motion of the arm 232 is transferred to the arm 234 by the link 233 and, thus, the shaft 235 is caused to rotate back and forth and thereby cause the collector table 244 to swing transversely and back and forth through the previously-mentioned vertical plane passed between the jaws of the stripping mechanism 14. This swinging reciprocal movement of the table 244 is synchronized with the movement of the stripping apparatus 14, so that, as the stripping apparatus carries a freshly-striped stocking 16 upwardly and into collecting position, the table swings underneath the stripping apparatus and collects or receives the stocking from the stripper, the cam 49 and its adjustable quadrant 49c (FIG. 12) being adjusted, as previously described, to cause the stocking to be released by the jaws of the stripping mechanism a moment after the lip 243 of the table 244, or the leg portions of the previously-collected stockings, come into swinging contact with the leg portion of the stocking then held by the stripping apparatus, thereby permitting the stocking to be received in neatly-stacked position upon the table 244 and upon the top of the stack of the stockings on the table. As seen in FIG. 2, as another stocking is received by the table 244 and released from the gripping jaws of the stripping mechanism, the leg portion of the newly-received stocking and the leg portions of the previously-stacked stockings are clamped between the lip 243 of the table 244 and the clamp plate 260.

This clamping action positively holds the stack of stockings in place as the table and its contents swing to the right, as viewed in FIG. 2, and as they subsequently begin their return swinging movement. The clamp plate 260 and its support arm 252 swing with the table during the actual receipt by the table of a new stocking, and on the return swing of the table 244 the stop button 251b of the stop wing 251a engages the end of the adjustable

screw 145c to stop the motion of the clamp plate 260 and thus separate the clamp 260 from the table 244 and its contents.

In summary, then, the table 244 swings laterally back and forth, collecting the stockings successively from the stripping mechanism 14 as the latter mechanism strips and carries the stockings, one by one, upwardly to the collecting position.

As the stripping mechanism 14 approaches the collecting station or position—that is, as the stripping mechanism approaches the upper end of its stroke—the leg of the freshly-striped stocking is hanging vertically below the stripping mechanism and in the path of the collecting table 244 and its end lip 243. Just as the stripping mechanism 14 reaches the uppermost end of its stroke and momentarily dwells there, the table 244 and its lip 243 come into swinging contact with the hanging portion of the stocking, the table at this time swinging from the left to the right, as viewed in FIG. 2. At the moment the stocking is contacted by the table 244, the clamp plate 260 is spaced only slightly to the right of the leg of the stocking about to be collected, so that the stocking is almost immediately clamped between the clamp plate 260 and the lip 243 of the table. At about this same moment the jaws of the stripping mechanism 14 are opened to release the foot of the stocking. The table swings on through the position formerly occupied by the hanging leg of the stocking, carrying the stocking and the clamp plate 260 to the right (again as viewed in FIG. 2). This continuation of the swing of the table to the right causes the stocking to be collected upon the table in the manner seen in FIG. 2, the foot of the stocking, and also in some cases a portion of the leg, being, in effect, progressively received upon and laid out on the table (or upon the stack of goods on the table) as the table swings beneath and past the stripping mechanism 14. During this collection of the new stocking upon the table (or on top of the stack on the table) the new stocking is positively clamped by the clamp plate 260 and is thus under positive control. The upper side of the foot portion of the new stocking also tends to brush across the lower edge of the depending skirt on the lowermost portion of the jaw 159 during the actual collection of the new stocking on the table, with the result that the foot portion of the new stocking is received in a nicely spread out and flat condition upon the table or upon the top of the stack of goods on the table.

The collection of the new stocking upon the table 244 is completed during the swing of the table to the right, as viewed in FIG. 2. Upon completion of its stroke to the right, the table 244 reverses its direction and swings back to the left, preparatory to making another collection. Upon the return stroke, the clamp plate 260 separates from the table and releases its clamping action on the newly-collected stocking when the stop pad 251b comes into stopping contact with the stop-screw 145c. The clamp plate 260 is thus stopped in a "ready" position during the return stroke of the table, this "ready" or normal position of the clamp plate being in the path of the table assembly but slightly to the right of the path along which the dangling leg of the next stocking will be carried by the stripping mechanism 14 as the latter mechanism delivers the next stocking to the collecting position or station. Consequently, the stopped, or "ready," position of the clamp plate 260 is such as not to interfere with the delivery of the next stocking to the collecting position, but yet is such that the clamping action on the next stocking will take place immediately after the next stocking is contacted by the table 244.

During the completion of the swing of the table 244 to the right (again as viewed in FIG. 2), and during the return swing of the table to the left, the stripping mechanism 14 makes its return stroke and begins its stripping action on the next stocking. This starts another cycle, the timing being such that, as the next stocking is brought

by the stripping mechanism into collecting position, the table 244, which will have completed its return stroke to the left, will again be making a collection stroke to the right and will sweep into contact with the next stocking the moment the latter reaches the collecting position. This cycle of operation is repeated over and over as the table collects the stockings accurately and in a neat and orderly fashion.

In operating the machine, the operator, as previously mentioned, stands in front of the apparatus and applies stockings, one after another, to the freshly-striped hosiery boards 12 which continuously move across the front portion of the machine after leaving the stripping zone. In FIG. 1, a freshly-striped hosiery form is shown at the front of the machine ready to have a stocking slipped thereon. From the front of the machine the hosiery forms 12 and the stockings 16 thereon are moved through the opening 63 into the interior of the treating chamber 11 where the forms 12 and the hosiery thereon are stacked in side-by-side position, as previously explained, and are slowly moved through the treating chamber for appropriate treatment of the hosiery.

The hosiery boards 12 with the treated hosiery thereon emerge from the treating chamber 11 through the opening 74 at the same rate as the hosiery forms enter the treating chamber. The hosiery forms emerge from the treating chamber 11 through the exit opening 74 and along the previously-mentioned straight portion of the conveyor track. As the forms emerge from the treating chamber, they immediately reach the stripping zone where the stripping mechanism 14, on its return stroke, straddles the foot of the stocking on that form 12 which has just reached the stripping zone.

As the stripping mechanism 14 begins its upward and forward stroke, the cam 49 actuates the switch-valve mechanism 201, 202 to cause the diaphragm 170 in the stripping mechanism to be inflated and thus move the movable jaw 177 of the stripping mechanism into position wherein the foot portion of the stocking on the form is clamped between the movable jaw 177 and the fixed jaw 159 of the stripper mechanism. As this clamping action takes place, the horizontal component of motion of the stripping mechanism is substantially equal to the horizontal forward movement of the hosiery form 12, so that the vertical component of motion of the stripping mechanism causes the heel and foot portion of the stocking initially to be raised substantially vertically with respect to the form. This initial vertical lifting of the stocking with respect to the form tends to free the heel portion of the stocking from the heel portion of the form, so that the stocking may thereupon be more easily stripped from the form. Immediately after this lifting action on the stocking takes place, the linear motion of the stripping mechanism 14 is accelerated, due to the shape of the "banana-shaped" cam 115, 116 (FIG. 7), so that the stocking is quickly and efficiently stripped from the form. The stripping mechanism advances up the support rod 124 and the stabilizing and guide track 144 to deliver the stocking to the collecting position, the stripping mechanism decelerating as it reaches the collecting position.

As previously discussed, due to the shape of the cam 115, 116, the stripper mechanism 14 dwells at the collecting position momentarily as the swinging collector table 244, which has already begun its sweep from the left to the right, as viewed in FIG. 2, comes into contact with the leg portion of the stocking suspended from the jaws of the stripper mechanism. As the lip 243 of the table 244 (or the leg portions of the previously-collected stockings) come into contact with the leg of the stocking about to be collected, the leg of the latter stocking is clamped by the clamp plate 260, thus establishing positive controls over the stocking about to be collected. Momentarily thereafter, and as the table swings through the vertical plane extending between the jaws of the stripper mechanism, the air under pressure is released from beneath the diaphragm

170 by the action of the cam 49, whereupon the movable jaw 177 of the stripper mechanism is moved to its open position by the coil springs 183, thereby releasing the new stocking from the collector mechanism and permitting that stocking to be received on the collector table.

10 While the newly-received stocking is being collected on the table 244 at the collecting stations, the form 12, from which that stocking has just been stripped, is moved from the stripping zone to the front of the machine where the operator may apply another stocking thereto.

15 It will be noted that all of the functions and operations of the machine are arranged to take place in proper synchronization, so that the machine is entirely automatic, except for the fact that an operator initially places each stocking upon a form 12 and may manually remove the stack of stockings from the table 244. The speed of the machine may be conveniently controlled by the operator through the use of the speed-control wheel 41 and, if desired, a hosiery form may be omitted on the transport mechanism following each group of 12 forms or some other predetermined number, so that the operator will have adequate time to reach up and remove the stack of collected stockings from the table 244, each time the predetermined number of stockings has been collected. The omission of the form just referred to permits the operator to function at maximum speed without failing to apply a stocking to a form during the moment required to remove the accumulated stack of stockings from the table 244.

20 While a presently-preferred form of the machine embodying the apparatus of the present invention and adapted to carry out the method of the present invention has been illustrated in the drawings and described above in detail, it will be apparent that numerous changes and variations 25 may be made therein within the spirit and scope of the appended claims. Merely by way of example, it will be apparent that the collecting or shuttle means, which in the above-described embodiment is the table 244, need not be a swinging table or shuttle in the sense that it moves about an axis. In some embodiments of the invention, it may be desirable that the table or shuttle move linearly and transversely with respect to the plane of stripping. Similarly, numerous changes may be made in the table or shuttle and in some cases it may be desired to employ 30 means for removing the stockings from the table or shuttle, either one by one as the stockings are received upon the table, or in groups after a stack has been collected thereon. It is intended that these and other variations of the invention be covered by the claims appended hereto.

35 50 I claim:

1. The method of depositing a hosiery article upon a stack of like articles, comprising the steps of moving the stack back and forth endwise along a predetermined path, gripping and suspending the next hosiery article by its foot portion in position wherein the leg portion of said next article hangs downwardly and intersects said predetermined path, whereby said hanging leg portion is engaged and laterally displaced by said stack during said movement thereof, and releasing the grip on the foot portion 40 of said next hosiery article during said movement of said stack and after the engagement thereof with said leg portion of said next hosiery article, whereby to deposit said next hosiery article upon the top of the stack.

45 60 65 70 75 2. Apparatus for handling a hosiery article or the like boarded upon an upstanding form, comprising means for gripping the foot portion of the hosiery article and for stripping the article from the form and carrying said article to a receiving station wherein the major portion of the article hangs downwardly, a platform, means for moving said platform endwise along a predetermined path into displacing engagement with the hanging portion of said hosiery article, and means for actuating said gripping means to release its grip upon said foot portion of said article during said movement of said platform and after

said engagement of said platform with said article, thereby to deposit said article upon said platform.

3. Apparatus for handling a hosiery article or the like boarded upon an upstanding form, comprising means for gripping the foot portion of the hosiery article and for stripping the article from the form and carrying said article to a receiving station wherein the major portion of the article hangs downwardly, a platform, means for moving said platform endwise along a predetermined path into displacing engagement with the hanging portion of said hosiery article, means for clamping said hanging portion of said article to said platform during said movement of said platform and after said engagement thereof with said article, and means for actuating said gripping means to release its grip upon said foot portion of said article during said movement of said platform and after said engagement of said platform with said article, thereby to deposit said article upon said platform.

4. Apparatus for handling a hosiery article or the like boarded upon an upstanding form, comprising means for gripping the foot portion of the hosiery article and for stripping the article from the form and carrying said article to a receiving station wherein the major portion of the article hangs downwardly, a platform having an end portion thereon, means for moving said platform along a predetermined path to bring said end portion of said platform into lateral displacing engagement with said hanging portion of said hosiery article above the lowermost extremity thereof, and means for actuating said gripping means in timed relation to said movement of said platform to release the grip upon said foot portion of said article during said movement of said platform and after said engagement of said end portion of said platform with said article, thereby to deposit said hosiery article upon said platform with a portion of said article draped downwardly over said end portion of said platform.

5. Apparatus for handling a hosiery article or the like, comprising means for gripping the foot portion of a hosiery article and for suspending said article at a receiving station in a position wherein a major portion of said article hangs downwardly, a platform, means for moving said platform endwise along a predetermined path into displacing engagement with the hanging portion of said hosiery article, and means for actuating said gripping means to release its grip upon said foot portion of said article during said movement of said platform and after said engagement of said platform with said article, thereby to deposit said article upon said platform.

6. Apparatus for handling a hosiery article or the like, comprising means for gripping the foot portion of a hosiery article and for suspending said article at a receiving station in a position wherein a major portion of said article hangs downwardly, a platform, means for moving said platform endwise along a predetermined path into displacing engagement with the hanging portion of said hosiery article, means for clamping said hanging portion of said article to said platform during said movement of said platform and after said engagement thereof with said article, and means for actuating said gripping means to release its grip upon said foot portion of said article during said movement of said platform and after said engagement of said platform with said article, thereby to deposit said article upon said platform.

7. Apparatus for handling a hosiery article or the like, comprising means for gripping the foot portion of a hosiery article and for suspending said article at a receiving station in a position wherein a major portion of said article hangs downwardly, a platform having an end portion thereon, means for moving said platform along a predetermined path to bring said end portion of said platform into lateral displacing engagement with said hanging portion of said hosiery article above the lowermost extremity thereof, means for clamping the engaged and displaced portion of said article to said end portion of said platform, and means for actuating said gripping means

in timed relation to said movement of said platform to release the grip upon said foot portion of said article during said movement of said platform and after said engagement of said end portion of said platform with said article, thereby to deposit said hosiery article upon said platform with a portion of said article draped downwardly over said end portion of said platform.

8. Apparatus for handling a hosiery article or the like, comprising a platform having a generally horizontally disposed collecting surface thereon, means for moving said platform back and forth along a predetermined path in endwise directions, means for gripping and suspending a hosiery article by its foot portion in position wherein a portion of the hosiery article hangs downwardly and intersects said predetermined path, whereby said hanging portion of said hosiery article is engaged and laterally displaced by said platform during the movement of said platform along said path, and means for actuating said gripping means to release its grip upon said foot portion of said article during said movement of said platform and after said engagement of said platform with said article, thereby to deposit said article upon said platform.

9. Apparatus for handling a hosiery article or the like, comprising a platform having a generally horizontally disposed collecting surface thereon, means for moving said platform back and forth along a predetermined path in endwise directions, means for gripping and suspending a hosiery article by its foot portion in position wherein a portion of the hosiery article hangs downwardly and intersects said predetermined path, whereby said hanging portion of said hosiery article is engaged and laterally displaced by said platform during the movement of said platform along said path, means for clamping said laterally displaced portion of said hosiery article to said platform, and means for actuating said gripping means to release its grip upon said foot portion of said article during said movement of said platform and after said engagement of said platform with said article, thereby to deposit said article upon said platform.

10. The combination set forth in claim 9, wherein said platform is pivotally mounted for movement about a fixed axis.

11. The combination set forth in claim 9, wherein said platform is pivotally mounted for movement about a fixed axis and said clamping means is also mounted for movement about said axis.

12. The combination set forth in claim 9, wherein said platform has a notch in an end thereof overlaid by said hosiery article when said hosiery article has been received upon said platform, whereby said hosiery article, while resting on said collecting surface, may be gripped between a thumb and forefinger preparatory to removal of said hosiery article from said platform.

13. The combination set forth in claim 9, wherein said platform is saddle-shaped and said collecting surface thereon is provided with transversely extending nap-bearing means tending to prevent the hosiery article from slipping upon said surface.

14. In stocking handling apparatus including a plurality of stocking receiving forms movable in succession along a given path, the combination comprising, a stripping carriage, means for guiding said stripping carriage along a second path between a stripping station adjacent the path of said forms and a collecting station, a pair of plates mounted on said carriage in spaced relation to receive between them the foot portion of a stocking on a form when the carriage is at the stripping station, a layer of soft spongy material on at least one of the opposed faces of said plates, means for moving one of said plates toward the other for gripping the foot portion of a stocking upon a form positioned between said plates at said stripping station, means for propelling said carriage along said second path from said stripping station to said collecting station to strip said stocking from said form and deliver

21

said stocking to said collecting station in a position wherein a portion of the stocking hangs below said carriage and said plates, a platform, means for moving said platform through said collecting station below said plates and into laterally displacing engagement with said hanging portion of said stocking while said carriage is at said collecting station, and means for retracting one of said plates in a direction away from the other while said platform is moving through said collecting station, thereby to release the grip on said stocking and permit the stocking to be received upon said platform.

15. The combination set forth in claim 14, wherein said platform is moved by said platform moving means below said carriage and said plates along a third path transversely of the planes of said plates, whereby said platform sweeps said stocking from between said plates and onto said platform as said platform moves through said collecting station.

16. The combination set forth in claim 15, wherein one of said plates extends downwardly and has a lower edge across which said stocking is swept by said platform, thereby smoothing said stocking as it is swept from between said plates and onto said platform.

17. In stocking handling apparatus including a plurality of stocking receiving forms movable in succession along a given path, the combination comprising, a stripping carriage, means for guiding said stripping carriage along a second path between a stripping station adjacent the path of said forms and a collecting station, a pair of plates mounted on said carriage in spaced relation to receive between them the foot portion of a stocking on a form when the carriage is at the stripping station, nap-bearing surfaces carried by the opposed faces of said plates with a layer of soft spongy material being interposed between at least one of said plates and the nap-bearing surface car-

ried thereby, means for moving one of said plates toward the other for gripping between said nap-bearing surfaces the foot portion of a stocking upon a form positioned between said plates at said stripping station, means for propelling said carriage along said second path from said stripping station to said collecting station to strip said stocking from said form and deliver said stocking to said collecting station in a position wherein a portion of the stocking hangs below said carriage and said plates, and means at said collecting station for receiving said stocking from between said plates and said nap-bearing surfaces.

18. The combination set forth in claim 17, wherein the nap-forming fibers of said nap-bearing surfaces which grip the heel of said stocking are directed upwardly and the nap-forming fibers on the remainder of said nap-bearing surfaces are directed in the direction of movement of said carriage from said stripping stations to said collecting station.
